UNITED STATES PATENT OFFICE.

EDWARD D. CLAPP, OF WASHINGTON, DISTRICT OF COLUMBIA.

COMBINED CYCLOMETER AND SPEED-INDICATOR.

SPECIFICATION forming part of Letters Patent No. 644,578, dated March 6, 1900.

Application filed April 1, 1898. Serial No. 676,069. (No model.)

To all whom it may concern:

Be it known that I, EDWARD D. CLAPP, a citizen of the United States of America, residing at Washington, District of Columbia, have 5 invented certain new and useful Improvements in a Combined Cyclometer and Speed-Indicator; and I do hereby declare the following to be a full, clear, and exact description of the invention, such as will enable others 10 skilled in the art to which it appertains to make and use the same.

This invention is a combined cyclometer and speed-indicator for bicycles and velocipedes, the object of the same being to provide 15 a device of this character which is positioned at a convenient point in front of the rider and will accurately indicate whether or not he is maintaining a certain speed at which the instrument has been previously set.

20 The invention is designed more particularly for use by racing wheelmen, forming practically a mechanical "pace-setter" that will keep the rider advised of the pace or speed at which his machine is moving, making it 25 possible for him to conveniently ascertain whether he is keeping up with or passing a certain record. The instrument is intended to supplant the practice in vogue of setting a pace through the medium of riders upon 30 tandems or polycycles, which practice presents objectionable features that are overcome by said instrument.

Though primarily intended as a pace-setter, it will appear hereinafter that the device 35 also forms a cyclometer for ordinary use and presents a conveniently-located timepiece, the latter feature being an essential adjunct to the proper operation of the pace-setter.

To the accomplishment of the objects hereinbefore noted, the invention consists of a 40 timepiece or watch having a supplemental hand geared thereto, differential gears mounted within the watchcase, one of said gears being provided with graduations, while the 45 other carries an indicator-finger or pointer, and a star-wheel geared to the aforesaid differential gears, said star-wheel being actuated by a tappet on one of the wheels of the bicycle.

50 The invention further consists of certain details of construction and combinations of

parts, fully described in the following specification and more particularly set forth in the appended claims.

In the accompanying drawings, which form 55 a part hereof, Figure 1 is a side elevation of the invention applied and including only so much of a bicycle as will illustrate such application. Fig. 2 is a plan view of the combined cyclometer and speed-indicator. Fig. 3 is a 60 side elevation, partly in section. Fig. 4 is an elevation of the star-wheel or actuating mechanism, including the supporting-bracket. Fig. 5 is a modification of the gearing mechanism between the star-wheel and cyclometer. Fig. 65 6 is a modification of the gearing between the timepiece and speed-indicator. Fig. 7 is a plan view of sets of removable gears for different speeds.

In carrying out my invention I employ, in 70 the first instance, a timepiece or watch of any approved make, though essentially regulated to run perfectly, said watch being designated in the drawings by the letter A. The casing of this watch is extended above the dial-plate, 75 terminating in a removable ring a, carrying a face-plate or crystal a', and interiorly said extension provides an annular flange or bearing-shoulder b, while on one side is formed a tangential housing or tube b'. Seated upon 80 the annular bearing-shoulder b is a ring or annular plate C, having a certain number of peripheral gear-teeth—for instance, 144—and mounted upon this plate is a second annular plate D, preferably of narrower width and 85 having one hundred and forty-five peripheral gear-teeth, or one more than the aforesaid plate, for the purpose hereinafter explained, said plates being retained in place by an expandible ring E. One of the annular plates, 90 the lower, is divided around its inner edge into spaces or graduations, over which travels an indicator-finger or pointer d, carried by the other plate, and with the teeth of both of said plates meshes a worm F, bearing within 95 the tube or housing b' and extended beyond one end of the same to receive a grooved pulley f, as shown in Figs. 1, 2, and 3, or a bevel-wheel S, as shown in the modification Fig. 5. It will be here noted that by reason of the dif- 100 ferent gears with which the worm meshes the plate C will lose the space of one tooth upon

each rotation of the plate D, the spaces between the graduations each representing a certain number of spaces which the former plate has dropped and correspond with a certain 5 number of revolutions of the bicycle-wheel to which the worm is geared, as hereinafter described, and determine the distance traveled by said wheel. In the present instance each mark or graduation on the annular plate C 10 represents twelve miles, and said plate is shown as having a capacity of one hundred and forty-four miles, though it could be made to actuate a train of gearing or digit-wheels to record a larger number of miles when the device 15 is to be used principally as a cyclometer. G designates a star-wheel by which the revolutions of the bicycle-wheel are transmitted to the worm of the cyclometer through the intervention of a tappet h on a spoke of said 20 bicycle-wheel, which engages the star-wheel, and suitable gearing between the shafts of the star-wheel and worm. This gearing can be accomplished in any well-known or approved manner, though I have shown but two 25 styles, Figs. 1, 2, and 3 illustrating a belt connection, while Fig. 5 shows the connection or gearing made through a vertical shaft. Figs. 1 and 4 show the shaft of the star-wheel arranged horizontally in a bearing-sleeve i 30 and carrying a grooved pulley k, over which passes an endless cord K from the grooved pulley f on the end of the worm. In this case the bracket I has a flat spring i', which bears against the grooved pulley k and offers a friction 35 device to regulate the throw of the star-wheel when struck by the tappet. This forms a very effective gearing and is the one which I prefer, as it will not add any material weight to the bicycle and can be readily thrown out 40 of gear when desired. The gearing illustrated in Fig. 5 consists of a vertical shaft M, bearing at its upper end in a sleeve t, carried by a watchcasing and at its lower end connected by collar m to a helical spring N, which is 45 secured to the shaft of the star-wheel, said shaft being disposed vertically in its supporting-bracket O. The spring takes up what vibration may occur in the frame of the bicycle, but is of sufficient rigidity to properly transmit 50 the power. At the upper end of the shaft M is a bevel-wheel P, in mesh with the bevel-wheel S on the worm-shaft.

The supporting-bracket which carries the star-wheel or actuating mechanism is provided 55 at its lower end with an opening by which it is placed upon the axle of the front wheel, and it is held in place by a nut. The tappet carried by a spoke of the front wheel of the bicycle is preferably a small roller, as 60 shown. The watch or casing of the instrument is supported from the stem of the handle-bars of the bicycle by means of a bracket R, presenting spring-clips or clamping-jaws r, connected by a tightening-screw r' and 65 tending rearward from a plate presenting spring-fingers R', which embrace the lower

part of the watch or casing, one of the fingers engaging the watch-stem, and forms a member over which the ring is passed to serve as an additional hold.

70 So much of my invention forms a very simple and effective cyclometer in connection with a watch or timepiece, though of course the latter feature could be dispensed with by mounting the differential gears and intermeshing worm in an independent casing. The watch or timepiece, however, is essential in completing the pace-setter or speed-indicator, which I shall now proceed to particularly describe.

80 The seconds-hand of the watch is removed from its arbor, and upon said arbor is fixed a pinion u, which meshes with a gear-wheel U, loosely mounted on the arbor of the hour-hand of the watch, and said gear-wheel carries a pointer or pointers u', which travel above the plane of the indicator-finger or pointer d. The gearing of the gear-wheel with the timepiece is such with respect to the 85 gearing of the annular plate D with the wheel 90 of the bicycle that both said gear-wheel and plate will rotate synchronously when the bicycle travels at a certain rate of speed. Therefore it is contemplated to so gear the parts as to predetermine the speed—for instance, 95 indicating the speed on the basis of a mile in two minutes and ten seconds. In order to change the ratio, it is only necessary to change the gearing between the pinion u and gear-wheel u' either by increasing the size of one 100 with respect to the other or by the arrangement illustrated in Fig. 6. In said figure a gear-wheel V is mounted upon the arbor of the hour-hand and is provided with a concentric series of crown-teeth v, with which is 105 adapted to mesh a pinion w, mounted upon a horizontal shaft W to slide longitudinally thereon, engaging a feather, said shaft also carrying a fixed pinion w', meshing with a pinion x on the seconds-hand arbor of the 110 watch. The shaft W is journaled in suitable bearings, and the movable pinion w thereon is shifted by means of a lever Y, having a bifurcated end engaging a groove in the hub of the pinion, said lever having a frictional contact with its pivot sufficient to hold it in an 115 adjusted position, though any device could be used for the purpose.

120 The modification just described, and illustrated in Fig. 6 of the accompanying drawings, forms the subject-matter of a divisional application for patent filed May 17, 1899, Serial No. 717,210.

125 From the foregoing description, in connection with the accompanying drawings, the construction and operation of my improved cyclometer and speed-indicator will be readily apparent. It will be seen that I provide an instrument of this character that is not only comparatively simple and cheap in its 130 construction and arrangement, but also possesses the more important advantage of being

accurate and of great assistance to any wheelman who desires to regulate the speed at which he is propelling his bicycle.

Though I have shown and described the device as being attached to the stem of the handle-bars of the bicycle and geared to actuating means located at the hub of the front wheel, it will be understood that said device could be located at the head of the front fork, with the tappet applied to the outer end of the spoke or to the rim of the wheel. Other obvious modifications could be adopted without sacrificing any of the inherent advantages of the invention, and I therefore declare that I do not confine my protection to what is herein precisely shown and described, but reserve the right to modify or change the construction within the spirit and scope of my claims.

In the drawings I have illustrated the gearing which forms part of the speed-indicator or pace-setter as located below the regular hands of the watch or chronometer, the arbors being extended for this purpose; but it will be understood that said gearing could be located below the hands, if so desired. The arrangement herein shown and described is, however, the preferred form, as it enables the gear-wheels to be quickly changed in setting the device for different speeds and is essential when the construction or gearing shown in Fig. 6 is employed.

Fig. 7 illustrates a convenient manner of carrying several sets of gears which are adapted to change the speed indicated by the combined movement of the watch mechanism and cyclometer. The smaller gear-wheel, which fits upon the seconds-hand arbor, is provided with a square opening to receive the squared end of said arbor, while the larger gear-wheel of each set has a circular opening, so that it will have a free movement on the arbor of the hour-hand or other shaft supporting it centrally within the watchcasing.

Having thus particularly described the detail parts of my invention and the several operations of which it is susceptible, what I claim as new, and desire full protection upon, is—

1. In a speed-indicator for vehicles, the combination with a watch or chronometer, of an indicator-plate, mechanism actuating the indicator-plate from a wheel of the vehicle, a gear-wheel removably mounted upon an arbor and turning loosely thereon, an indicator actuated by said gear-wheel, and a second gear-wheel removably mounted upon an arbor, the last-mentioned gear-wheel being driven from the watch-movement and geared to the former gear-wheel, substantially as shown and for the purpose herein set forth.

2. In a speed-indicator for vehicles, the combination with a watch or chronometer, of an indicator-plate rotatably mounted above the dial-plate of the watch or chronometer, mechanism transmitting motion to the indicator-plate from a wheel of the vehicle, a gear-wheel removably mounted upon an arbor above the

dial-plate and adapted to turn loosely upon said arbor, an indicator carried by said gear-wheel, and a second gear-wheel also removably mounted upon an arbor; the last-mentioned gear-wheel being driven from the watch-movement and geared to the former gear-wheel, substantially as shown and for the purpose set forth. 75

3. In a speed-indicator for vehicles, the combination with a watch or chronometer having a central arbor extended above the dial-plate, of an indicator-plate rotatably mounted above the dial-plate, mechanism transmitting motion to the indicator-plate from a wheel of the vehicle, a gear-wheel removably mounted upon the aforesaid central arbor of the watch and adapted to turn loosely upon said arbor, an indicator carried by said gear-wheel, and a second gear-wheel also removably mounted upon an arbor which is actuated by the watch-movement, the last-mentioned gear-wheel being geared to the former gear-wheel, substantially as shown and for the purpose set forth. 90

4. In a speed-indicator for vehicles, the combination with a watch or chronometer having a central arbor extended above the dial-plate and a second arbor also extended above the dial-plate, the last-mentioned arbor being driven from the watch-movement; of an indicator-plate rotatably supported above the dial-plate, mechanism transmitting motion to the indicator-plate from a wheel of the vehicle, a gear-wheel removably mounted on the central extended arbor and adapted to turn loosely upon said arbor, an indicator carried by said gear-wheel, and a second gear-wheel removably mounted upon the other extended arbor and adapted to turn therewith, the last-mentioned gear-wheel meshing with the former gear-wheel, substantially as shown and for the purpose set forth. 105

5. In a combined speed-indicator and cyclometer, the combination with a watch or chronometer, of indicator-plates rotatably mounted above the dial-plate of the watch, one of said plates having graduations and the other a pointer or indicator, mechanism transmitting motion to the indicator-plates from a wheel of the vehicle, a gear-wheel removably mounted above the dial-plate upon an arbor upon which it turns loosely, an indicator carried by said gear-wheel, and a second gear-wheel removably mounted upon an arbor 120 which is driven from the watch-movement, the last-mentioned gear-wheel being in mesh with the former gear-wheel, substantially as shown and for the purpose set forth. 115

6. In a speed-indicator for vehicles, the combination with a watch or chronometer, of an indicator-plate rotatably mounted above the dial-plate of the watch, mechanism transmitting motion to the indicator-plate from a wheel of the vehicle, a central arbor above the dial-plate, and a second arbor extended above the dial-plate and driven from the watch-movement; together with gear-wheels adapted to be removably mounted on the

aforesaid arbors, and an indicator actuated by the gear-wheels, substantially as shown and for the purpose set forth.

7. In a combined speed-indicator and cy-
5 clometer, the combination with a watch or
chronometer, of a central arbor extended
above the dial-plate, a second arbor extended
above the dial-plate and driven from the
watch-movement, indicator-plates rotatably
10 supported above the dial-plate, one of said
indicator-plates having graduations and the
other a pointer or indicator, and mechanism
transmitting motion to the indicator-plates
from a wheel of the vehicle; together with
15 several sets of gear-wheels adapted to fit upon
the extended arbors, one of the gear-wheels
of each set being loosely mounted and carry-
ing an indicator while the other is adapted
to turn with its arbor and gear with the
20 former, substantially as shown and for the
purpose set forth.

8. In a combined speed-indicator and cy-
clometer, the combination with a watch or

chronometer, of a central arbor extended
above the dial-plate, a second arbor extended 25
above the dial-plate and driven from the
watch-movement, annular plates of different
width rotatably supported above the dial-
plate and provided with coincident teeth, one
of said plates having a greater number of 30
teeth than the other, the wider plate having
graduations and the other an indicator; a
worm in mesh with the toothed plates, and
mechanism imparting motion to the worm
from a wheel of the vehicle; together with 35
several sets of gear-wheels, said gear-wheels
fitting the aforesaid extended arbors and one
of each set carrying an indicator, substan-
tially as shown and for the purpose set forth.

In testimony whereof I affix my signature 40
in presence of two witnesses.

EDWARD D. CLAPP.
